J. H. HUME,
FURNACE FRONT,
APPLICATION FILED SEPT. 12, 1917.

1,331,152.

Patented Feb. 17, 1920.

UNITED STATES PATENT OFFICE.

JAMES HOWDEN HUME, OF GLASGOW, SCOTLAND, ASSIGNOR TO JAMES HOWDEN & COMPANY, LIMITED, OF GLASGOW, SCOTLAND, A CORPORATION OF GREAT BRITAIN.

FURNACE-FRONT.

1,331,152.

Specification of Letters Patent.

Patented Feb. 17, 1920.

Application filed September 12, 1917. Serial No. 191,056.

To all whom it may concern:

Be it known that I, JAMES HOWDEN HUME, a subject of the King of the United Kingdom of Great Britain and Ireland, and residing at Glasgow, Scotland, have invented a certain new and useful Improvement in Furnace-Fronts, of which the following is a specification.

This invention relates to fronts for forced draft furnaces and has for its primary object to provide a construction whereby the furnace is adapted to burn economically either coal alone or oil alone or both coal and oil, the arrangement being such that the change from one type of fuel to the other can be immediately effected without the necessity for removal or replacement of fire-bars.

Fronts for furnaces operating on the well known Howden forced draft system are fitted at each side of the firing entrance with a valve-controlled air port, for passage of air to the under side of the grate, the side valve operating gear being operatively connected with means for locking the furnace door in such wise that the side valves must be moved to closed position before the door can be opened.

A furnace front of the kind just referred to is shown in U. S. patent to Howden, No. 923,178, dated June 1, 1909, and the present invention relates to certain novel features whereby the Howden furnace is adapted to burn either coal or oil, or both, without changing or removing any of the parts.

A preferred form of furnace front embodying the present invention is illustrated in the accompanying drawing in which Figure 1 is a front elevation of a furnace front constructed in accordance with the present invention, Fig. 2 is a section on line 2-2, Fig. 3, looking in the direction of the arrows adjacent said line, and Fig. 3 is section on line 3-3, Fig. 1, looking in the direction of the arrows adjacent said line and with some parts omitted. Fig. 4 is an enlarged detail view showing the connections between the furnace door locking lever and the oil supply valve.

Referring to the drawing, the improved furnace front comprises a casting 1 having side flues at each side of the firing entrance *a*, as in the construction shown in the Howden patent above referred to. The admission of air to the furnace grate through said

side flues is controlled by butterfly valves 2 mounted on a spindle 3, as set forth in the Howden patent above referred to.

The firing entrance chamber *a* is provided at its sides with openings *b* communicating with air chambers *c* having openings or ports *d* at their tops for the admission of air to said chambers. The admission of air through the said openings or ports *d* is controlled by sliding valves 6 operated by arms 6^a on the inside of the front plate of the furnace, said arms being connected with arms 6^b on the outside of the said front plate. The said arms 6^b are preferably connected by a link 7 so that the sliding valves 6 will be simultaneously operated.

The improved furnace front is provided, above the firing entrance *a*, with an air chamber 8 having, at its top, openings 10 controlled by a sliding valve 11, said valve 11 being connected by a link 11^a with an arm 11^b inside of the front plate of the furnace front, said arm 11^b being provided with an operating handle 11^c on the outside of the front plate of the furnace. Mounted to extend into the air chamber 8 is an oil burner 9 which may be supplied with oil through a pipe 13, and the supply of oil to said burner is controlled by a turning valve at 12. The oil supply valve may be opened 85 and closed by an arm 12^a jointed at 14 to a link 15 which is in turn jointed to a sliding bar 16 provided with a pin 17 which engages the furnace door locking lever 5, so that when the said slide is lifted to open 90 the oil admission valve said locking lever will be moved to the position denoted by dotted lines in Fig. 1, to lock the furnace door 4, so that the said door cannot be opened when the oil burner or burners are 95 in operation, while the oil supply will be cut off before said door can be opened. When the oil valve is open the arm 12^a will be in line with the adjacent portion of the oil supply pipe 13, or approximately so.

From the foregoing it will be understood that the present invention provides separate chambers through which coal and oil may be introduced to the furnace, the coal being introduced through the firing entrance chamber *a* and the oil through the chamber 8. It will also be understood that the admission of air to the said chambers is controlled by separate valves, so that either oil or coal, or both, may be used as fuel, and the air

supply may be properly regulated according to the combustion desired. Thus if coal is being burned alone the air supply may be shut off from the chamber 8 communicating with the oil burner or burners, while the air supply to the air chambers connected with the firing entrance for coal may be closed if oil alone is being consumed. It will also be understood that the furnace door 10 4, closing the firing entrance chamber *a*, cannot be opened when the oil supply is turned on.

What I claim is:—

1. A furnace front, for use in burning coal 15 or oil, or both, having a firing entrance chamber for use in burning coal, air controlling and guiding chambers located partly above the said firing entrance chamber and partly at the sides thereof and into 20 which said firing entrance chamber opens, said air controlling and guiding chambers being provided at their tops with valve-controlled ports for the admission of air, an oil admission chamber above the said firing en-

trance, an oil burner fitted in said last-named chamber which is also provided at its top with valve-controlled ports for the admission of air. 25

2. A furnace front, for use in burning coal or oil, or both, having a firing entrance 30 for use in burning coal, a door for closing said entrance, means for locking said door, an oil burning chamber located above the said firing entrance, an oil burner fitted in said chamber, an oil supply pipe extending 35 to said burner, and oil fuel controlling means operatively connected with said locking means and arranged to cut off the supply of oil before the door of said firing entrance can be opened. 40

In testimony whereof I have signed my name to this specification in the presence of two subscribing witnesses.

JAMES HOWDEN HUME.
